Byron Hume Groce & Clement
Attn:

center contacts 36 and 37 are elevated above those at each side as will be clear from the showing in FIGURE 1.

The carrier 12 is adapted to ride in the slot 25, and in addition to the bridging contacts 40, 41 and 42 which are mounted on the carrier, the said carrier has the armature 17 secured thereto. Each bridging contact is located in an opening 43, 44 and 45 respectively formed in the carrier and a coil spring such as 46 yieldingly maintains its respective contact against the bottom wall of its opening. When the bridging contacts are thus positioned it will be seen that they function as a normally open circuit arrangement since the main coil spring 47 confined between the base structure and the armature yieldingly biases the carrier in an upward direction. This maintains the bridging contacts spaced above the stationary contacts and it is necessary to energize the magnet 14-15 to attract the armature and move the carrier down to cause the bridging contacts to close their respective circuits.

In accordance with the invention the carrier 12 is formed with an alternate opening for the center bridging contact 41, the opening being identified by the numeral 48 (FIG. 13). The said alternate opening is located directly below the opening 44 and the same is reversed with respect thereto. Accordingly, when the center bridging contact 41 is disposed in the opening 48 it is located below the stationary contacts 36 and 37 and thus the arrangement provides for a normally closed circuit. This alternate form is fully disclosed in FIGURE 7.

In keeping with the stepped arrangement of the stationary contacts it will be observed that the top surface of the carrier is also stepped and sliding movement of the carrier is facilitated by the elongated projection 50 (FIG. 13) on each side of the carrier and which ride in the grooves 27. The present magnetic contactor is relatively compact although sufficiently rugged and durable to have a long life even under the most severe operating conditions. The arc block is readily detachable from the plastic base structure and this accordingly facilitates removal of the armature and of the carrier for inspection and for repairs or replacement.

The invention is not to be limited to or by details of construction of the particular embodiment thereof illustrated by the drawings, as various other forms of the device will of course be apparent to those skilled in the art without departing from the spirit of the invention or the scope of the claims.

What is claimed is:

1. In a magnetic contactor, the combination with a base member of plastic material, said base member substantially encasing a coil and magnet device such that only the top of the magnet projects a short distance above and centrally of the top surface of the base member, of an arc block also of plastic material and providing on its top surface a plurality of longitudinally extending channels formed by upstanding side walls and spaced centrally located upstanding partitions, the bottom wall of one of said channels being disposed in a plane above the remaining channels, said arc block having a transverse opening therein and which is in alignment with the projecting end of the magnet, a pair of stationary contacts fixed to the bottom wall of each channel so that a contact is located on each side of the opening, a carrier mounted in the opening and adapted to have movement towards and from the magnet, said carrier having a plurality of openings therein extending from side to side, a bridging contact in each opening and projecting beyond its open-

ing on each side, whereby the bridging contacts coact with their respective stationary contacts when the carrier is actuated, an armature fixed to the carrier at the base thereof adjacent the magnet, and a coil spring confined between and having contact with the armature and the top surface of the base member.

2. In a magnetic contactor, the combination with a base member formed of plastic material, of an arc block of insulating material fixedly secured to the top side of the base member, said base member substantially enclosing a coil and magnet device such that only the magnet projects exteriorly from the top side of the base, said arc block having a transverse opening therein and which is disposed in alignment with the projecting magnet, a plurality of stationary contacts fixed to the arc block and arranged longitudinally in pairs with the contacts of each pair being located on respective sides of the opening, at least one pair of said stationary contacts being disposed in a plane above the other pairs of stationary contacts, a movable carrier located in the opening, said carrier having openings therein equal in number to the number of pairs of stationary contacts plus an extra opening, bridging contacts equal in number to the pairs of stationary contacts and located in openings in the carrier, whereby a bridging contact coacts respectively with each pair, an armature fixed to the carrier and disposed relatively adjacent the projecting magnet, and a coil spring confined between the base member and said armature, said extra opening in the carrier providing for selective location of a bridging contact whereby the circuit arrangement including the same may be either normally open or normally closed.

3. In a magnetic contactor, in combinations, an arc block having side walls and partition walls forming three longitudinally extending passages, said arc block having a transverse opening formed therein and extending from side wall to side wall, a plurality of stationary contacts fixed to the arc block and arranged longitudinally in pairs with the contacts of each pair being located on respective sides of the opening, the center pair of stationary contacts being disposed in a plane above the other two pairs, a movable carrier located in the opening, said carrier having openings therein equal in number to the number of pairs of stationary contacts plus an extra opening, bridging contacts equal in number to the pairs of stationary contacts and located in openings in the carrier, whereby a bridging contact coacts respectively with each pair of said stationary contacts, and an armature fixed to the carrier, said extra opening in the carrier being located centrally for utility with the center stationary contacts, and said extra opening providing for selective location of a bridging contact whereby the circuit arrangement including the said bridging contact may be either normally open or normally closed.
